HARRY BLAND STRANGE, OF SHEFFIELD, ENGLAND, ASSIGNOR TO THOMAS FIRTH
AND SONS, LIMITED, OF SHEFFIELD, ENGLAND.

FUSE FOR A PROJECTILE.

1,077,439.

Specification of Letters Patent.

Patented Nov. 4, 1913.

Application filed October 4, 1911. Serial No. 652,796.

To all whom it may concern:

Be it known that I, HARRY BLAND STRANGE, a subject of the King of England, and residing at Sheffield, in Yorkshire, England, have invented a new and Improved Fuse for a Projectile, of which the following is a specification.

This invention relates to an improved fuse for a projectile and has particular reference to a projectile filled with an explosive which is required to burst it on the impact of the projectile with its objective.

A fuse for a projectile of this type is often provided with a cartridge which when the impact takes place moves forward and is exploded to ignite the bursting charge either directly or through the action of an intermediate charge. The cartridge is generally retained by some form of safety device in a position where it is away from the detonating needle or other device which causes the explosion of the cartridge such safety device being withdrawn or sheared when the impact occurs.

In fuses as hitherto manufactured there has been considerable risk of the bursting of the projectile if the cartridge has been accidentally exploded when in its normal position and the primary object of this invention is to so construct the fuse that the tube or chamber containing the cartridge will only burst if the cartridge explodes when it is in one particular position of the tube namely the part to which it travels when impact has occurred between the projectile and its objective. This is accomplished according to this invention by providing the fuse with a tube or chamber of rifle steel or other material of great tensile strength having a comparatively weak portion which will burst if a cartridge explodes in it but will not burst if the explosion occurs at some other place in the tube.

The accompanying drawing is a central section through one construction of fuse according to this invention.

The fuse illustrated is a base fuse having a screw-threaded body A adapted to be screwed into the base of a projectile but the construction may be modified so that the fuse is mounted in some other position, say at the nose of the projectile.

Into a threaded socket in the body A, is screwed one end of a tube B, of rifle steel or other material of great tensile strength.

The walls of a portion of the tube are of such thickness relatively to the bore as to withstand the explosive force of a cartridge of high power. In other words, the tube is made of material of approximately the same tensile strength and cross sectional dimensions as a rifle barrel, the bore and thickness of the tube illustrated in the drawings being those of the .303 rifle barrel. A portion B' of the tube intermediate the ends is weakened, as for instance by making the walls of the tube thinner. In order to support the tube between the end beyond the weakened portion and the base so as to prevent rupture of the tube by inertia or momentum, a casing C employed which surrounds the tube, the tube B being provided with a screw thread where it engages the inner end of the casing C, the latter screwing into the body of the fuse.

Contained partly in the lower end of the tube B and partly in a cavity in the body A forming a continuation of the bore of the tube, is a cartridge D of fulminate of mercury or other high explosive. This is normally retained in the position shown in the drawings by a pin E of some hard metal having one end which is adjacent to a disk F formed as a punch. This disk F is of thin metal and is held up against the punch-like end of the pin E by a screwed plug G. Adjacent to the other end of the pin E is a chamber containing some deformable material such as soft lead H which is in contact with the end of a plunger J capable of moving in a chamber A' in the fuse body. The head of the plunger is covered by a cup disk K to which the gases generated on the discharge of the gun can have access through openings in a screw plug A² which closes the chamber A'. At the other end of the tube B a screw plug L is fitted bearing a detonating needle L' which projects down the bore of the tube until its point is adjacent to the comparatively weak portion B'. 100

In operation the cartridge D is normally retained in the position shown in the drawings until on the discharge of the gun the pressure of the gases generated acting upon the deformable metal H causes it to fly and to force the pin E out of its hole in the cartridge D. In its movement the pin perforates the disk F and enters a hole G' in the screwed plug G. The comparatively hard pin E is thus removed from the car- 110

tridge and there is substituted for it a pin of comparatively soft metal which will be easily sheared on even a slight impact. When impact occurs the soft shearing pin 5 is sheared and the cartridge moves forward inside the weak portion B' of the tube where it is exploded by the detonating needle L' and bursts the weak portion of the tube thus igniting an explosive charge in 10 the spaces M and M' between the tube and the casing. It will be seen that the tube B is provided with a flange B² covered on each side by a disk N of balloon or like material. The object of this is to divide up 15 the space between the tube and the casing and to prevent the explosive charge which is packed in that space from setting back when the projectile is fired. It will be understood that the explosive in these spaces 20 is not the bursting charge proper of the projectile but is intended to ignite the main bursting charge which is packed around the casing C.

If by any combination of accidental circumstances 25 the cartridge D should be exploded when it is in any other part of the tube B except the weaker portion B' the tube B is not fractured and consequently the charge in the spaces M and M' is not exploded. The weak portion of the tube may in some cases be at the extremity of the tube B but preferably it is positioned as shown in the drawing some small distance from the end of the tube remote from the 30 normal position of the cartridge. There is then some space in the tube beyond the weak portion and the presence of this space lessens the risk of the weak portion being burst if the cartridge is accidentally exploded when in some other part of the tube. For the same purpose the screwed plug L carrying the detonating needle L' may in 35 some cases be perforated and a space left on the other side of it to form what may be termed an expansion chamber for the gases. It will be understood that the presence of this chamber or space beyond the weak portion of the tube only has a practical effect in the event of accidental explosion of the 40 cartridge when it is not in the weak portion of the tube. When it is in that weak portion the action is extremely rapid and the bursting of the weak part of the tube occurs immediately.

55 It is to be understood that the tube of strong material having a weak portion which will burst if a cartridge explodes in it but will not burst if the explosion occurs in some other place in the tube may be applied to other forms of impact fuses and is 60 only illustrated by way of example in a fuse in which a safety device of lead or other weak material is substituted for one of stronger material.

What I claim as my invention and desire 65 to secure by Letters Patent is:—

1. In a fuse for a projectile the combination of a tube of great tensile strength having one portion comparatively weak, a cartridge adapted to travel in such tube, a safety 70 device for retaining the cartridge normally in the strong portion of the tube, means within the tube adjacent to the weak portion thereof for exploding the cartridge and means operated by the pressure of the gases 75 generated on the discharge of the gun for removing said safety device and substituting for such safety device another retaining member which is easily sheared when the impact occurs. 80

2. In a fuse for a projectile, the combination with a fuse body, of a tube carried thereby of such tensile strength and cross sectional dimensions as to withstand the explosive force of a cartridge of high power, 85 and a weakened portion intermediate its ends, and a casing mounted on the fuse body for supporting the weakened portion of the tube to normally prevent its deformation. 90

3. In a fuse for a projectile, the combination with a fuse body having a portion thereof of such tensile strength and cross sectional dimension as to withstand the explosive force of a cartridge of high power, 95 and a weakened portion intermediate its ends, a casing mounted on the fuse body and supporting the weakened portion of the tube and to normally prevent the deformation of the weakened portion and a supplementary explosive charge surrounding the 100 tube and within the casing. 100

4. In a fuse for projectiles, the combination with a fuse body, of a tube having a portion of such tensile strength and cross 105 sectional dimension as to withstand the explosive force of a cartridge of high power, a weakened portion intermediate its ends, and a casing mounted on the fuse body and supporting the weakened portion of 110 the tube, and a flange on the tube dividing the space between the tube and casing into two compartments and supplementary charges in such compartments. 115

5. In a fuse for a projectile the combination of a fuse body, a casing mounted thereon, a tube or chamber within such casing and axial therewith, such tube being of great tensile strength but having a comparatively weak portion near the end remote 120 from the fuse body, a detonating needle mounted in such tube adjacent to the weak portion thereof, a cartridge of explosive material adapted to travel in the tube, a safety device for retaining the cartridge normally 125 at that portion of the tube remote from the detonating needle, a chamber in the fuse body adjacent to the safety device, a de-

formable substance in such chamber and means operated by the pressure of the gases generated on the discharge of the gun for causing such deformable substance to dis-
5 place the safety device thereby forming a retaining member which is easily sheared when the impact occurs.

6. In a fuse for a projectile the combination of a fuse body, a casing mounted there-
10 on, a tube or chamber within such casing and axial therewith, such tube being of great tensile strength but having a comparatively weak portion near the end remote from the fuse body, a detonating needle mounted in such tube adjacent to the weak portion thereof, a cartridge of explosive material adapted to travel in the tube, a shearing punch for retaining the cartridge normally at that portion of the tube remote from the
15 detonating needle, a chamber in the fuse body adjacent to the safety device, a deformable substance in such chamber, a plunger bearing against the deformable substance and a disk or diaphragm adjacent to the plunger and exposed to the pressure of the gases generated on the discharge of the gun so that such pressure is transmitted from the disk through the plunger to the deformable substance for the pur-
20 pose set forth.

7. In a fuse for a projectile the combina-

tion of a fuse body, a casing mounted thereon, a tube or chamber within such casing and axial therewith, such tube being of great tensile strength but having a comparatively weak portion near the end remote from the fuse body, a detonating needle mounted in such tube adjacent to the weak portion thereof, a cartridge of explosive material adapted to travel in the tube, a shearing punch for retaining the cartridge normally at that portion of the tube remote from the detonating needle, a disk adjacent to said punch, a chamber in the fuse body adjacent to the shearing punch, a deformable substance in such chamber, a plunger bearing against the deformable substance and acted upon by the pressure of the gases generated on the discharge of the gun so that the deformable substance displaces the
35 shearing punch causing it to perforate the disk and substitute for such shearing punch a retaining member which is easily sheared when the impact occurs.

In testimony whereof I have signed my
40 name to this specification in the presence of
two subscribing witnesses.
